UNITED STATES PATENT OFFICE.

WALLACE E. WROCINSKI, OF CHICAGO, ILLINOIS.

CURTAIN HANGER.

Application filed October 19, 1921. Serial No. 508,760.

To all whom it may concern:

Be it known that I, WALLACE E. WROCINSKI, a citizen of the United States, and a resident of Chicago, in the county of Cook 5 and State of Illinois, have invented a new and useful Improvement in Curtain Hangers, of which the following is a full, clear, and exact description.

My invention relates to improvements in 10 curtain hangers, and it consists in the combinations, constructions and arrangements herein described and claimed:

An object of my invention is to provide 15 a device of the type described in which the rods from which the curtains are suspended may be lowered to permit the curtains to be placed thereon or removed without the use of a step ladder or the like.

A further object of my invention is to 20 provide a device of the character described in which a plurality of rods may be supported parallel to one another and lowered and elevated simultaneously.

A further object of my invention is to 25 provide a device of the character described which is extremely simple in construction and thoroughly effective for the purpose intended.

Other objects and advantages will appear 30 in the following specification, and the novel features of the invention will be particularly pointed out in the appended claims.

My invention is illustrated in the accompanying drawings, forming part of this application, in which

Fig. 1 is a front elevation of an embodiment of my invention,

Fig. 2 is a sectional view along the lines 2—2 of Fig. 1,

Fig. 3 is a side elevation of one of the brackets viewed from the line 3—3 of Fig. 1,

Fig. 4 is a side elevation of one of the brackets showing a modified form of the rod support,

Fig. 5 is a sectional view along the line 5—5 of Fig. 1, and

Fig. 6 is a front elevation viewed from the line 6—6 of Fig. 5.

In carrying out my invention, I provide 50 two cast metal brackets 1 and 2, which are adapted by means of wood screw members 3 to be secured to a window or door frame 4. The brackets are usually fixed to the frame 4 in the positions shown in Fig. 1, one at 55 each side thereof. The brackets 1 and 2 are provided each with a slot 5. A pulley wheel

6 is rotatably mounted within the slot 5 and arranged to project above the upper surfaces 7 of the brackets. The bracket 1 is provided with a V-shaped slot 8, one branch 60 of which lies in the main body 9 of the bracket and the other in a wing portion 10. The wing portion 10 is disposed at 90° from the body portion 9 of the bracket and is on the right side of the body portion 9 as it 65 is viewed from the front. The bracket 2 is also provided with a V-shaped slot 11, one branch of which lies in the main body 12 of the bracket and the other in a wing portion 13, which is also disposed at 90° from the main body 12, but unlike the bracket 1 is disposed on the left side of the main body 12 as the bracket is viewed from the front. Each branch of the V-shaped slots 70 8 and 11 is provided with pulley wheels 14 and 15, respectively. The slots 5 and the V-shaped slots 8 and 11 extend clear through their respective brackets.

Supporting members 16 and 17 provide 75 means for supporting curtain rods 18 and 19. The rods 18 and 19 have holes 20 disposed adjacent their ends and are arranged to engage upwardly extending hook members 21 and 22 of the supporting members 16 and 17. The rods 18 and 19 may be removed 80 from their supporting members 16 and 17 by merely lifting them out of engagement with the hook members 21 and 22.

A flexible cable 23 is secured at one end 85 to the supporting member 16, as shown in dotted lines in Fig. 1 at 24. The cable 23 is then run over the tops of the pulleys 5 and 14 of the bracket 2 and under the pulley 15 of the bracket 2. The cable 23 then runs to and over the pulley wheel 15 of the bracket 90 1 and extends therefrom vertically down through an eyelet 25, which eyelet is secured to the frame 4, as shown at 26. The supporting member 17 has also attached thereto a flexible cable 27 which is secured 100 to the supporting member 17, as shown at 28. The cable 27 runs up from the supporting member 17 over the tops of the pulley wheels 6 and 14, and from thence down through the V-shaped slot 8 through the 105 eyelet 25. It will be seen at this time that unless the cables 23 and 27 are secured in some manner relative to the brackets 1 and 2 that the supporting members 16 and 17, would drop by their own weight. Means for 110 restraining the movement of the cables 23 and 27 is provided in a plate 28 having

holes 29 and 30 through the upper portion thereof. The ends of the cables 23 and 27 are secured to the plate 28 through the openings 29 and 30, respectively, as shown in Fig. 6. The plate 28 is provided with a central opening 31 therethrough. A fastening button 32 is secured by means of a wood screw base 33 to the frame 4 within reach of a person standing on the floor adjacent the frame 4. The button 32 has at its outer end a slot 34 in which a locking plate 35 of approximately the width as the diameter of the button 32 is slidably and rotatably mounted. This structure is clearly shown in Fig. 5. 10 When the locking plate 35 is in the position shown in dotted lines in Fig. 5, the plate 28 may be slipped upon the bottom 32, as shown in full lines in the drawing. If the locking plate 35 is then moved to the position shown 15 in full lines, the plate 28 will be locked securely thereon.

A hook member 36 is arranged to be removably secured to the plate 28 through a hole 37 at the lower end thereof. The hook 25 36 has attached to it a cord 38, the purpose of which will be hereinafter described.

From the foregoing description of the various parts of the device, the operation thereof may be readily understood. Normally the rods from which the curtains or drapes are suspended are in the position shown in Fig. 1. When it is desired to change the curtains or remove them, the hook 36 is secured to the plate 28 through the 30 opening 37. The locking plate 35 is then moved to the position shown in dotted lines in Fig. 5. This will enable the operator to remove the plate 28 from the button 32 and by holding the cord 38 in the hand, to slowly 35

pay out the cord until the rods 18 and 19 40 are down within reach of the operator. The rods 18 and 19 may then be removed from their supporting members 16 and 17 and curtains placed thereon or new ones replaced for soiled ones, as the case might be. The 45 eyelet 25 also acts as a stop for the plate 28 and thus limits the drop of the rods 18 and 19.

In Fig. 4, I have shown a modified form 50 of the rod supporting member, which consists in a supporting member 39 which is provided with but one hook portion 40 and is therefore intended for the support of only one rod, as is shown at 41.

I claim:

A device of the character described comprising a rod for suspending curtains or the like therefrom, a pair of supporting members adapted to support each one end of said rod, a pair of brackets, each of said brackets having a pulley wheel rotatably mounted thereupon, a pair of flexible cables, one arranged for travel and support upon each of said pulley wheels, each of said cables secured at one end to one of said supporting members, and means associated with the other ends of said cables for securing said cables against longitudinal movement thereof, said means comprising a plate securely fastened to the said other ends of said cables, 60 said plate having an opening therethrough, a button adapted to be secured to a window casing or the like at which said rod is supported, and a lock plate carried by said button for locking said button through said 65 opening in said plate.

WALLACE E. WROCINSKI.
